Inventor,

Frederick H. Casey

UNITED STATES PATENT OFFICE.

FREDERICK H. CASEY, OF GARDNER, MASSACHUSETTS.

INKWELL.

Application filed April 18, 1922. Serial No. 554,413.

This invention relates to improvements in a combined ink well, paper weight and pen stand and has for its purpose among other objects to provide a pen and ink stand with an ink well and a fountain whereby the well may be supplied from time to time with a relatively small quantity of ink.

Another object of the invention is to provide in an ink well, means for holding for use, a relatively small quantity of ink and a fountain for supplying said ink.

Another object of the invention is to provide a pen and ink stand having an ink well and an invisible or entirely enclosed fountain for supplying said well.

With the above and other objects in view I have invented the device illustrated in the accompanying drawings in which—

Figure 1 is a top plan view of my combined ink stand;

Figure 2 is a front elevational view thereof;

Figure 3 is a side elevational view thereof;

Figure 4 is a section on line 4—4 of Figure 1;

Figure 5 is a detailed top plan view of an ink fountain;

Figure 6 is an elevational view thereof;

Figure 7 is a section on line 7—7 thereof; Figure 8 is a similar view, the parts being shown in adjusted position;

Figure 9 is a section on line 9—9 of Figure 1;

Figure 10 is a detailed elevational view partly broken away of one member of an ink fountain;

Figure 11 is a similar view of another member thereof;

Figure 12 is a detailed perspective view of a fountain operating member;

Figure 13 is a similar view of a member of said fountain;

Figure 14 is a perspective view of another member thereof;

Figure 15 is a section on line 15—15 of Figure 16, certain parts being removed; and

Figure 16 is a section on line 16—16 of Figure 4.

Like reference characters indicate like parts throughout the following specification and in the several views in the drawings in which, 1 indicates an ink stand which embraces a base 2 having a main body portion 3 and an inclined forwardly projecting portion 4 provided with a series of spaced apart

ribs 5 which form grooves 6 for holding pens or pencils. 7 are grooves arranged transversely of said ribs in order to provide finger spaces in order that said pens and pencils may be easily picked from said grooves. 60 The main body portion 3 is provided with a vertical bore 8 in its rear central portion which is connected through an aperture 9 with an inclined ink well 10 the upper end of which terminates in the central forward portion 11 of the upper surfaces 12 of said base 3. Seated within said bore 8 is an ink fountain or reservoir 13 which consists of an outer fixed cylinder 14, and a rotatable inner cylinder 15, having a detachable screw 70 threaded closure end 16 with a projecting milled flange 17 whereby said member 15 may be easily removed for the purpose of thoroughly cleansing the well.

Fixedly secured to the upper portion of 75 the cylinder 14 is a relatively large supporting flange 18, which is adapted to seat upon the upper surface 12 of said body portion 3, whereby the reservoir is held sustained within the bore 8. Rotatably mounted around 80 the cylinder 14 is a collar 19 which seats directly under and against the flange 18. This collar is provided with right angularly disposed oppositely arranged arms 20 and 21 which incline in opposite directions. The 85 lower ends of these arms terminate adjacent oppositely disposed horizontal slots 22 and 23 and are provided with apertures 24 and 25 through which the projecting ends 26 and 27 of the pin 28, fixedly mounted in the inner cylinder 15, extend, whereby upon the rotation of the collar 19 by means of its projecting handle 29 the cylinder 15 is rotatable within the cylinder 14 in order that the slots or apertures 30 in the cylinder 15 90 may be brought into alignment with the slots or apertures 31 in the cylinder 14, whereby a desired amount of ink within the fountain 13 may be allowed to flow into the well 10. A spring clip 32 is mounted on the handle 29 100 in order that its right angular end 33 may project below either of the edges 34 or 35 of the flange 36 providing a stop, in order to prevent accidental movement of said cylinder 15. The flange 36 is arranged to project beyond the rear wall 37 on the body portion 3. When it is desired to move the inner cylinder 15 to release the supply of ink to the well 10 the clip 32 is pressed down so that its end 33 will ride over its 110

flange 36 and allowed to drop over the edge 34 thus bringing said slots or apertures 30 and 31 into alignment.

The forward arcuate edge 38 of the member 18 is provided with a hinge member 39 which co-acts with the hinge member 40 of the top 41 of the ink well 10 to receive the pintle 42 whereby said top is hingedly secured to said member 18. The top 41 is provided with a spring clip 43 at its forward end for engagement with the recesses 44 in said body portion 3, said clip having a finger portion 45 whereby the clip may be released from said recesses to raise the top. The body portion 3 has projecting upwardly from its surface 12 bosses or dowel pins 46 adjacent each side thereof to enter the recesses 47 in the removable top portion 48 of the stand, said portion 48 being provided with a bore 49 which aligns with the bore 8 in the base 2 and into which the upper portion 50 of the reservoir or fountain 13 projects, said reservoir or member 48 forming a closure for said fountain. The forward side 51 of the member 48 is provided with a relatively large cylindrical recess 52 within which the outlet 53 of the ink well 10 partially projects.

The walls of bore 8 are provided with oppositely arranged bayonet slots 54 and 55 to receive the extended end of the member 28 whereby the cylinder 14 may be held within the bore 8 so that when emptying ink therefrom for the purpose of cleansing the device or renewing the ink supply, said member 14 cannot become accidentally detached from the body 3.

From the above description it will be obvious that the supply of ink in the fountain 13 may be kept from exposure to the air whereby evaporation will be prevented, however, a small quantity of the ink may be supplied as desired to the well 10. It will be noted that the apertures 30 provided in the inner cylinder 15 are above the closure member 16, said member being adapted to receive and maintain all sediment in the ink and thus preventing the same from being supplied to the well.

Having described my invention that which I claim to be new and desire to procure by Letters Patent is—

1. An inkstand comprising in combination separable base and top members, said members having aligning bores, an ink reservoir mounted in said bores, and an ink well communicating therewith and carried by the base member, the top member adapted to cover the reservoir.

2. An ink stand comprising in combination, a base member having a bore therein, an ink reservoir consisting of a pair of nested cylinders, mounted in said bore, an ink well communicating with said reservoir and carried by the base member, and means

extending from said reservoir for rotating one of said cylinders relative to the other, whereby to manually control delivery of ink from the reservoir to the ink well.

3. In combination with an ink stand having an ink well and a bore connected therewith, a reservoir consisting of a pair of nested cylinders seated in said bore and means for rotating one of said cylinders relative to the other cylinder, a screw threaded bottom on one of said cylinders.

4. In combination with an ink stand, an ink well and a reservoir for supplying said well, means whereby said ink may be supplied to the well from the reservoir, said means embracing a rotatable collar projecting from said stand, and a rotatable cylinder within said reservoir, said cylinder and reservoir having apertures adapted to be aligned through the rotation of said cylinder, said stand having a bore and means for suspending said reservoir, within said bore, a closure member for said reservoir, said closure member consisting of a removable portion of said stand.

5. In combination with an ink stand, an ink well and a reservoir for supplying said well, means whereby said ink may be supplied to the well from the reservoir, said means embracing a rotatable collar projecting from said stand, and a rotatable cylinder within said reservoir, said cylinder and reservoir having apertures adapted to be aligned through the rotation of said cylinder, said stand having a bore and means for suspending said reservoir within said bore, a closure member for said reservoir, said closure member consisting of a removable portion of said stand, a top for said well having a spring clip for retaining the same in closed position, said top being hingedly connected to said last means.

6. In combination with an ink stand, an ink well and a reservoir for supplying said well, means whereby said ink may be supplied to the well from the reservoir, said means embracing a rotatable collar projecting from said stand, and a rotatable cylinder within said reservoir, said cylinder and reservoir having apertures adapted to be aligned through the rotation of said cylinder, said stand having a bore and means for suspending said reservoir, within said bore, a closure member for said reservoir, said closure member consisting of a removable portion of said stand, and means for holding said apertures out of alignment.

7. In combination with an ink stand, an ink well and a reservoir for supplying said well, means whereby said ink may be supplied to the well from the reservoir, said means embracing a rotatable collar projecting from said stand, and a rotatable cylinder within said reservoir, said cylinder and reservoir having apertures adapted to be

- aligned through the rotation of said cylinder, said stand having a bore and means for suspending said reservoir within said bore, a closure member for said reservoir, said closure member consisting of a removable portion of said stand, and means for holding said apertures out of alignment, and means for holding said apertures in alignment.
- 10 8. An ink stand according to claim 1, characterized by the top member being of such shape to conceal the ink reservoir and expose the ink well, when said base and top members are in connected relation.
9. In an ink stand in combination, a base member having a vertical recess therein, a pair of vertical nested cylinders supported on said base and within said recess, said nested cylinders having diametrically opposite slots in their walls, adapted to be brought into registry and to be blanked, said base also having an inclined ink well and communicating means between the same and the said recess, and means for selectively registering and blanking the slots of said nested cylinders.

In testimony whereof I affix my signature.
FREDERICK H. CASEY.
